(57) **CLAIM**

The ornamental design for a “flower package,” as shown and described.

DESCRIPTION

FIG. 1 is a perspective front left view of the flower package including a package cover showing my design;

FIG. 2 is a front view of the flower package of FIG. 1;

FIG. 3 is a rear view of the flower package of FIG. 1;

FIG. 4 is a top view of the flower package of FIG. 1;

FIG. 5 is a bottom view of the flower package of FIG. 1;

FIG. 6 is a left side view of the flower package, the right side view being essentially a mirror image thereof;

FIG. 7 is a plan view of the cover of the flower package of FIG. 1 shown separately for ease of illustration, the cover being flat with unadorned bottom;

FIG. 8 is a left front perspective view of the flower package of FIG. 1 with the package cover removed;

FIG. 9 is a plan view of the flower package of FIG. 1 with package cover removed, the flower package of FIG. 9 being folded flat in a two layer assembled position; and,

FIG. 10 is a plan view of the flower package of FIG. 1 with package cover removed, the flower package of FIG. 10 being folded flat in a one layer unassembled position.
